(57) **CLAIM**

The ornamental design of a handbag, as shown and described.

DESCRIPTION

FIG. 1 is a perspective view of a handbag;

FIG. 2 is a bottom plan view of a handbag;

FIG. 3 is a top plan view of a handbag;

FIG. 4 is a front elevational view of a handbag;

FIG. 5 is a rear elevational view of a handbag;

FIG. 6 is a left-side elevational view of a handbag; and,

FIG. 7 is a right-side elevational view of a handbag.

The broken lines immediately adjacent the shaded areas represent the bounds of the claim and all other broken lines are for illustrative purposes only. None of the broken lines form a part of the claimed design.
